MECHANICAL PENCIL

Max Stössel, Zurich, Switzerland

Application January 22, 1936, Serial No. 60,290
In Switzerland February 13, 1935

2 Claims. (Cl. 120—18)

Mechanical pencils are known in which the lead is propelled by turning a threaded member. It has been found advisable in such cases to provide the threads with but a slight pitch in order to eliminate the possibility of the lead pushing back the movable part of said threaded member and thus also pushing the lead back into the pencil when the lead is pressed down hard in writing. Furthermore, a great number of turns are required for pushing the lead forward and backward.

This disadvantage is overcome by the present invention by the provision of two threaded members which propel the lead with the aid of the propelling rod when turning one of them and by blocking the advance of the one of said members which is moved axially against any undesired shift by means of a laterally springy brake-stop.

In the accompanying drawing the object of the invention is illustrated in an example of design as a mechanical pencil for thin and flat leads, in which—

Fig. 1 is a longitudinal section of the pencil;

Fig. 2, a longitudinal section of the pencil 25 turned 90° about its axis;

Fig. 3, a lateral view of an example of the propelling rod;

Fig. 4, a cross-section along line a—b of Fig. 1;

Fig. 5, a cross-section along line c—d of Fig. 1;

Fig. 6, a cross-section along line e—f of Fig. 1;

Fig. 7, a cross-section along line g—h of Fig. 1;

Fig. 8, a cross-section along line i—k of Fig. 1;

Fig. 9, a cross-section along line l—m of Fig. 1;

Fig. 10, a section to a larger scale of the writing end of the pencil;

Fig. 11, a sketch for illustrating the adaptability of the latter; and

Figs. 12 and 13, a variation of the design of the propelling rod.

A shell 1 is drawn tightly onto a tube 2 so that by turning the shell the tube is also turned. Said tube, being provided with internal threads, is used as one of the two threaded members. Said tube contains a frame 3 lying with a smooth surface against threads 4. Said frame carries a head 14 possessing a stop-ring 16 which latter rests against an end of tube 2 and thus prevents any axial shifting of frame 3 relative to tube 2. A boss 6 of the orifice head 5 is securely fastened to the frame 3. Said frame 3 contains in its upper part two opposed slits 19 (Fig. 4), and between the latter is bent outwardly, and is somewhat elastically yielding in order to attain a brake-action between frame 3 and tube 2. In the finished pencil said frame is cylindrical over

its entire length, but possesses a spring-tension at right angles to its axis which acts in an outward direction. A threaded drive block 18 lies axially displaceable inside said frame 3 and projects laterally through the slits 19 and thus engages the threads 4 (Fig. 1). A short cylindrical knob 17, provided with spherical segments at both ends, is disposed inside said block 18, and is axially revolvable. Said knob thus may turn in recess 15 without being set obliquely to the axis of the pencil. Said knob furthermore, on the outside of said block 18, is rigidly connected to a head 13 (Fig. 3) which carries a narrow propelling rod 12 which latter, in the embodiment shown, possesses two laterally yielding legs 12a and 12b. Said rod 12 loosely and movably engages a leader-shell 8 whereby said legs act as brakes against the latter's inside wall. Said leader-shell carries a head 9 which may displace itself freely through a limited distance in a recess 7 of frame 3, said displacement being resisted by the braking action of rod 12. Said leader-shell 8 has a round cross-section around its circumference inside said orifice head 5, and on the inside the cross-section of a thin, rectangular and flat lead. Said leader-shell, at its lower end, is flattened down at both sides of part 8a, thus possessing an essentially rectangular cross-section on the outside. Said end of said shell 8 is cut off at an oblique angle (Fig. 10) and is provided with rounded edges 8b. The lower writing surface of lead 10, when writing, lies in the same plane as the lower frame-surface of part 8a (Fig. 10).

The threads with which the two threaded parts 2 and 18 engage may have a high pitch, since the brake-action between frame 3 and tube 2 prevents a turning of both said members relative to each other when lead 10 and part 8a are pushed down hard onto the writing-surface. Due to said high pitch, propelling of lead 10 is effected with a lesser number of turns than would be required in the case of threaded members with less pitch.

If lead 10, before being put to use, is not in the position according to Fig. 10, but drawn back, it may be brought into said position when screwing part 8a of the leader-shell 8 down onto the writing surface. The springy legs 12a and 12b then bring this latter movement to a stop so that, when lifting the pencil off the writing-surface, leader-shell 8 does not automatically drop off.

If the pencil is laid against a ruler 21 or the like with part 8a being in an oblique position according to the full lines of Fig. 11, it automati-

cally will turn with the arrow into position 8c parallel with the edge of the ruler.

The propelling rod 12 could also be spliced from head 13 downwardly in order to serve as a springy brake.

Two independent and individual springs, both bent toward the outside, also could be used as a propelling rod. Moreover, according to Figs. 12 and 13, a narrow spring could at one part of its length possess a longitudinal slit 12c and the two members 12d thus formed and lying adjacent to said slit could be bent sideways and toward the outside.

I claim:

- 15 1. In a mechanical pencil, an orifice head having a longitudinal cylindrical bore, a frame secured to said orifice head and having a chamber, said frame comprising a pair of outwardly bowed resilient rods forming a pair of laterally opening, longitudinally extending slots therebetween, an internally screw-threaded sleeve around said frame against which said bowed rods frictionally press, means on said frame for securing said sleeve against longitudinal displacement, a leader shell having an externally cylindrical portion within the bore of the orifice head, a head on the leader shell located in the chamber of the frame, said cylindrical portion and leader shell head being longitudinally slidable and rotatable in said bore and chamber respectively, said shell having a longitudinally extending opening of rectangular cross-section, a drive block mounted in said frame between the rods thereof and having screw threaded portions extending outwardly from the frame through the slots thereof and engaging with the threads of the surrounding sleeve, said block having a downwardly opening elongated socket formed therein, a propeller rod of rectangular cross-section extending into the rectangular opening of the leader shell, said rod having an elongated knob at its upper end disposed in the socket of the drive block for rotation about a longitudinal axis but held against lateral movement.
- 20 2. In a mechanical pencil, an orifice head having a longitudinal cylindrical bore, a frame secured to said orifice head and having a chamber, said frame comprising a pair of outwardly bowed resilient rods forming a pair of laterally opening, longitudinally extending slots therebetween, an internally screw-threaded sleeve around said frame against which said bowed rods frictionally press, means on said frame for securing said sleeve against longitudinal displacement, a leader shell having an externally cylindrical portion within the bore of the orifice head, a head on the leader shell located in the chamber of the frame, said cylindrical portion and leader shell head being longitudinally slidable and rotatable in said bore and chamber respectively, said shell having a longitudinally extending opening of rectangular cross-section, a drive block mounted in said frame between the rods thereof and having screw threaded portions extending outwardly from the frame through the slots thereof and engaging with the threads of the surrounding sleeve, said block having a downwardly opening elongated socket formed therein, a propeller rod of rectangular cross-section extending into the rectangular opening of the leader shell.
- 25 3. In a mechanical pencil, an orifice head having a longitudinal cylindrical bore, a frame secured to said orifice head and having a chamber, said frame comprising a pair of outwardly bowed resilient rods forming a pair of laterally opening, longitudinally extending slots therebetween, an internally screw-threaded sleeve around said frame against which said bowed rods frictionally press, means on said frame for securing said sleeve against longitudinal displacement, a leader shell having an externally cylindrical portion within the bore of the orifice head, a head on the leader shell located in the chamber of the frame, said cylindrical portion and leader shell head being longitudinally slidable and rotatable in said bore and chamber respectively, said shell having a longitudinally extending opening of rectangular cross-section, a drive block mounted in said frame between the rods thereof and having screw threaded portions extending outwardly from the frame through the slots thereof and engaging with the threads of the surrounding sleeve, said block having a downwardly opening elongated socket formed therein, a propeller rod of rectangular cross-section extending into the rectangular opening of the leader shell.
- 30 4. In a mechanical pencil, an orifice head having a longitudinal cylindrical bore, a frame secured to said orifice head and having a chamber, said frame comprising a pair of outwardly bowed resilient rods forming a pair of laterally opening, longitudinally extending slots therebetween, an internally screw-threaded sleeve around said frame against which said bowed rods frictionally press, means on said frame for securing said sleeve against longitudinal displacement, a leader shell having an externally cylindrical portion within the bore of the orifice head, a head on the leader shell located in the chamber of the frame, said cylindrical portion and leader shell head being longitudinally slidable and rotatable in said bore and chamber respectively, said shell having a longitudinally extending opening of rectangular cross-section, a drive block mounted in said frame between the rods thereof and having screw threaded portions extending outwardly from the frame through the slots thereof and engaging with the threads of the surrounding sleeve, said block having a downwardly opening elongated socket formed therein, a propeller rod of rectangular cross-section extending into the rectangular opening of the leader shell.
- 35 5. In a mechanical pencil, an orifice head having a longitudinal cylindrical bore, a frame secured to said orifice head and having a chamber, said frame comprising a pair of outwardly bowed resilient rods forming a pair of laterally opening, longitudinally extending slots therebetween, an internally screw-threaded sleeve around said frame against which said bowed rods frictionally press, means on said frame for securing said sleeve against longitudinal displacement, a leader shell having an externally cylindrical portion within the bore of the orifice head, a head on the leader shell located in the chamber of the frame, said cylindrical portion and leader shell head being longitudinally slidable and rotatable in said bore and chamber respectively, said shell having a longitudinally extending opening of rectangular cross-section, a drive block mounted in said frame between the rods thereof and having screw threaded portions extending outwardly from the frame through the slots thereof and engaging with the threads of the surrounding sleeve, said block having a downwardly opening elongated socket formed therein, a propeller rod of rectangular cross-section extending into the rectangular opening of the leader shell.

MAX STÖSSEL.
